UNITED STATES PATENT OFFICE.

ALFRED B. FOWLER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PUNCHING-MACHINE.

1,308,780.

Specification of Letters Patent.

Patented July 8, 1919.

Application filed April 24, 1915. Serial No. 23,690.

To all whom it may concern:

Be it known that I, ALFRED B. FOWLER, a citizen of the United States, residing at Beverly, in the county of Essex and State of Massachusetts, have invented certain Improvements in Punching-Machines, of which the following description, in connection with the accompanying drawings, is a specification, like reference characters on the drawings indicating like parts in the several figures.

This invention relates to punching machines and is herein illustrated in connection with a machine for forming an ornamental row of punch holes or perforations along the margin of pieces of upper leather which are to be used in the manufacture of boots and shoes.

The pieces of leather which are ornamented are of different contours and many of them have curved edges. Hitherto in machines of this class the direction of the feed movement of the machine has been fixed; and the operator has turned the stock manually when a curved margin was encountered. It is very difficult, however, when this procedure is carried out to secure uniform spacing of the perforations.

One feature of the present invention comprises in a machine of the class described a tool for operating upon the stock, means for feeding the stock past the tool, and means for varying the direction and extent of the feed during the operation of the machine. In the illustrative machine each intermittent feed movement of the feeding members starts always at the same point, said point being located as closely as practical to the axis of the punch. With this construction control of the direction of movement of the feed member is substituted for the former manual turning of the work; and the spacing of the punch holes is under control and practically uniform.

In machines of this class it is common to use hollow punches in combination with a backing strip of paper or other suitable material which is fed along underneath the leather and serves to receive the punches and cause them to cut clean holes. Another feature of the invention comprises improved feeding means for this backing strip.

These and other features of the invention including certain details of construction and

combinations of parts will be described in 55 connection with an illustrative machine and pointed out in the appended claims.

Referring to the accompanying drawings,—

Figure 1 is a side elevation of a machine 60 in which the present invention is embodied;

Fig. 2 is a perspective of the mechanism for operating the punch and the feed members;

Fig. 3 is an elevation of a portion of the 65 front of the machine;

Fig. 4 is a plan of the mechanism which controls the direction of feed movement, the parts being shown with the lower feed member at one extremity of its movement; 70

Fig. 5 is a plan similar to that of Fig. 4 and with the lower feed member shown at its opposite extremity of movement;

Fig. 6 is an elevation of part of the head 75 of the machine;

Fig. 7 is an elevation showing more particularly the connection between the link 39 and fulcrum block 40;

Fig. 8 is an elevation of the reel stand;

Fig. 9 is a side elevation of a portion of 80 this reel stand, showing more particularly its connection with the feed mechanism of the punching machine;

Fig. 10 is a detail showing the construction of the members which grip and feed 85 the stock.

Referring first to Figs. 1, 2 and 3, the stock is fed over a table 1 above which a punch 3 is reciprocated by means of a cam 5 fast to a driving shaft 11 and two rolls 90 7 which latter are mounted upon the punch holder or stem 9. The particular clutch mechanism shown in Figs. 1 and 2, which imparts rotation to the shaft 11 will not be described since the details of its construction form no part of the present invention and any suitable means for applying power to the shaft 11 may be employed. The upper feed member 13 is slidable in a casting 15 having an arm 17 which is pivoted 100 at 19 to a slide bar 21 mounted in suitable slide bearings in the head of the machine. The stem 23 of the feed member, which is of reduced diameter, is surrounded by a coiled spring 25 one end of which rests 105 against the feed member and the other end against the slide bar 21 so as to hold the said member down against a lower feed

member which will be described presently. A lever having a finger piece 26 is provided for lifting the feed member 13 manually when desired. The stem 23 passes loosely 5 through an arcuate slot (not shown) formed in an enlargement 210 at the end of the slide bar 21 as well as through a second arcuate slot 27 formed in the enlarged end of an actuating lever 29 and has 10 threaded upon its upper end adjusting nuts 31. The two arcuate slots are concentric with the axis of the pivot 19, and the casing 15 and presser foot 13 are free at all times to swing in a path determined by the location 15 of the pivot 19.

In order to give a reciprocating feed movement to the upper feed member 13 the slide bar 21 is reciprocated by the following mechanism: Pivoted at 33 to said bar 20 is a link 35 to the other end of which is pivoted at 37 an upwardly extending link 39, said link being slidable through a suitable bearing in a fulcrum block 40 which may be adjusted up and down by means of 25 a lever 41 to vary the location of the fulcrum. Any suitable form of bearing by which a link may slide through a fulcrum block may be used, the particular one employed in the present machine being shown 30 in detail in Fig. 7. The lever 39 is pivoted at 43 to a bar 45 slidably transversely of the shaft 11 and provided with rolls 47 which embrace a cam 49 on said shaft. This mechanism imparts reciprocation to the slide 35 bar 21 and hence to the upper feed member 13. This feed member is lifted intermittently by the lever 29 which is pivoted near its center at 51 to an ear on the slide bar 21 and at its outer end to a link 53 which in 40 turn is pivoted at 55 to a bell crank lever the end of the horizontal arm of which is shown at 57. The upright arm 58 of this lever (see Fig. 6) carries a roll 60 which is held in contact with a cam 59 on the shaft 45 11 by a spring as shown. With the construction thus far described the feed member 13 will be given the usual four-motion feed movement. It should be noted, however, that the member is free at the same 50 time to move in a path at an angle to the direction of movement of the slide 21 in that it may swing about the pivot 19.

The lower feed member comprises a loop 61 the purpose of which is to guide a paper 55 backing strip such as that shown, for example, in the patent to Flynt No. 941,704. On top of the loop is a circular member 68 which contacts with the under side of the stock; and depending from the loop is a 60 stem 63 which extends through an arcuate slot 65 formed in an enlarged portion of the slide bar 67. Said stem is connected with its slide bar 67 by a link 69 which is pivoted at 71 to the slide bar, said link 65 responding in function to the arm 17 which

connects the casing 15 of the upper feed member with the upper slide bar 21. It will be noted that the axis of the pivots 19 and 71 is the same and that both the upper and the lower feed members are capable of 70 swinging about this axis during the reciprocation of the slide bars 21 and 67.

In order to determine the direction of movement of the lower feed member and to vary said direction during the operation of 75 the machine in accordance with whether a straight or a curved edge is being operated upon, a guide link 73 pivoted at 75 to the frame of the machine embraces a roll 77 carried at the lower end of the stem 63. The 80 position in which this guide link is held thus determines the direction in which the lower feed member shall move and hence also the direction in which the upper feed member shall move since the two feed members are 85 pressed toward each other by the spring 25 of the upper feed member. Fast to or integral with the link 73 is an ear 79 which is connected by a link 81 with a lever 83 fulcrumed at 85 upon the machine frame and 90 having a handle 183. Referring now to Figs. 4 and 5 the effect of changing the position of this guide link 73 will be clear. In Fig. 4 the slide bar 67 is shown at the forward limit of its reciprocation, the parts 95 being in the same position as that shown in Fig. 3. In Fig. 5 the slide bar 67 is shown at the rear limit of its reciprocation. Therefore with the link 73 held in the position shown the lower feed member will move 100 back and forth in a direction determined by the position of said link 73. The link will be held in the position shown when the margin of the work has a curvature of a certain radius. If now it should be desired to operate upon a straight margin the link 73 would be swung about its pivot 75 until the center of the slot in said link was parallel 105 to the axis of the slide bar 67.

The slide bar 67 is reciprocated by a fork 110 87 the arms of which embrace a block 89 pivoted at 91 to said slide bar. This fork is fast to a rock shaft 93 which carries a slotted arm 95 connected by a link 97 with a second slotted arm 99 pivoted at its inner 115 end at 101 to the frame of the machine and at its outer end at 103 to a flat rod 105 carrying rolls 107 which embrace a cam 109 fast to the shaft 11. Rotation of the shaft 11 thus oscillates the rock shaft 93, the amplitude of oscillation depending upon the position in which the link 97 is held. This link slides through a block 111 fast to the end of a stud shaft 113 rotatable in fixed bearings in the frame of the machine; and the angular position of the block determines the amplitude of oscillation of the shaft 93. Thus the positions of the two blocks 111 and 40 determine respectively the extent of the feed movements of the lower and the upper 125 130

feed members. Obviously it is desirable that the two feed members should move to the same extent and that when the extent of movement of one is varied the extent of movement of the other should be varied an equal amount. For this reason the lever 41, which governs the position of the fulcrum block 40 is fast to one end of a rock shaft 115 the other end of which carries a sector 117 having teeth which mesh with the teeth of a second sector 119 fast to the stud shaft 113. Consequently when the lever 41 is moved to vary the extent of feed of the upper feed member 13, the shaft 115 is rocked and the block 111 moved angularly to change the position of the link 97 and thereby the extent of feed movement of the lower feed member, the parts of the mechanism being so constructed and arranged that the extent of forward and backward movement of the feed members is always equal. The lever 41 is clamped in adjusted position by means of a thumb screw 120 as best shown in Fig. 6.

Referring now more particularly to Figs. 3, 4 and 5 and disregarding for the moment the paper backing strip 62, the operation of the machine is as follows: Let it be supposed that a piece of leather 300 having a straight edge followed by a curved edge is to be operated upon. The handle 183 of the lever 83 is moved to bring the slot in the guide link 73 into line with the slide rod 67. Reciprocation of the slide rod 67 will then cause reciprocation of the lower feed member in the same direction and the leather will be fed intermittently straight ahead. When the curved edge of the leather is reached the handle 183 is moved to the right or the left according to the nature of the curve. In Figs. 4 and 5 it is shown as moved to its extreme left hand position as viewed in Fig. 2 with the guide link 73 extending at approximately 45° to the axis of the slide bar 67. The path of the lower feed member will be determined by the slot in the link 73, and in this case will extend from a point in the line of straight feed to a point at the right of said straight line feed as viewed in Fig. 2. By manipulating the lever 183 the operator can cause the angle of deflection of the feed to be varied at will either to the right or to the left. It should be noted that each intermittent feed, whatever its direction, always starts from the same point, this point being located as near as practical to the axis of the punch with the result that the spacing between the punched holes is substantially uniform. The upper feed member by reason of the action of the spring 25 follows the movements of the lower feed member in every case. If desired a guide link for the upper member similar to the guide link 73 may be provided although in the present machine it has not been considered desirable.

If the upper and lower feed members

which grip the stock were each integral throughout, it would be impracticable for the operator to turn the stock at all by hand. Such turning is, however, desirable at times particularly when an irregular curve is encountered. For this reason the disk 68 (see Fig. 10) of the lower feed member is rotatably mounted and supported on balls 20, and the upper feed member is furnished with a similar disk 14, similarly mounted. The movements of the feeding mechanism and punch are so timed that the stock is engaged by the feed mechanism or the punch at all times; and this construction and arrangement has the advantage that no presser foot such for example as that shown in the patent to Flynt referred to above is required.

Referring now to Figs. 3, 8 and 9 the manner in which the paper backing strip is fed forward and wound upon a reel will be described. A reel stand 121, see Fig. 8, carries a stud 123 upon which is rotatably mounted a reel carrier 125, said reel carrier in turn having two studs 127, 129 upon which are mounted reels 131, 133, the studs 127, 129 being rotatable in their respective bearings 135, 137. Studs 127, 129 have fast to their inner ends gears 139, 141 either of which may be caused to mesh with a gear 143 which is fast to a short shaft 145. The hub of a sprocket wheel 147 is held between a friction washer 149 and the bearing 153 by means of a coiled spring 151 one end of which rests against said bearing and the other against an adjusting nut 155 threaded on the shaft. A chain 157 passes around a sprocket wheel 159 and around the sprocket wheel 147 so that when the wheel 159 is rotated intermittently by mechanism presently to be described the gear 141 is turned in a direction to wind the backing strip on the reel 133 and to unwind it from the reel 131. From the reel 131 the backing strip runs over the pulley 161 and then through suitable guiding apparatus, which may be similar to that shown in the patent to Flynt referred to above which directs it over the punch block and back over the pulley 185 to the reel 133 upon which it is wound. The paper strip is fed by means of a gripper 163, see Fig. 3, the lower end of which is pivoted to the slide bar 67 and the upper end of which carries an arm 165 which bears upon the paper strip, a weak spring 167 being fastened at one end to the gripper 163 and at the other end to the slide bar 67. With this construction the rate of feed of the paper backing strip will always be equal to the rate of feed of the leather; and in order to make the rate at which the strip is wound up approximately equal to the rate of feed, the sprocket 159, see Fig. 9, is turned intermittently by the reciprocating slide bar 67 in the following manner: Pivoted upon the shaft 169 of the sprocket wheel is an arm 171

70

75

80

85

90

95

100

105

110

115

120

125

130

which is connected by a link 173 with the bar 67. Pivoted to the arm 171 at 175 is a pawl 177 which is held by a spring 179 in contact with a disk 170 fast to the shaft 169.

5 With former paper winding devices, such for example as that shown in the patent to Flynt, there has been a constant pull upon the paper at all times so that a constant and considerable slippage of parts has been provided for in order to prevent breaking the paper. With the present construction the only slippage necessary to provide for is that which results from the increasing size of the roll of paper on the reel 133, such slippage easily taking place by reason of the manner in which the hub of the sprocket wheel 147 is held. The paper backing strip in machines of this kind may be used several times; and in the present construction provision is made for moving the empty reel into the place of the full one and vice versa. To this end the bearings 135, 137 are provided with shallow sockets 181 either of which may receive the end of a spring 25 pressed locking pin 183. After the strip has been unwound from the reel 131 and wound upon the reel 133, the spring pin 183 is raised and the reel carrier 125 rotated 180° until the gear 139 meshes with the gear 143 and the end of the pin 183 enters the socket 181. The end of the paper strip is then passed around a pulley 161, through suitable guiding members and then back around the pulley 185 and fastened to the reel 131. Operation of the winding apparatus will then unwind the strip from the reel 133 and wind it upon the reel 131.

In order to permit adjustment of the punch 3 longitudinally two cams 190 and 191 are provided as shown in Fig. 1, the cam 191 carrying a pin 195 by which it may be turned, and being held in adjusted position by a screw-bolt 193.

Although the invention has been set forth in connection with a particular machine it should be understood that the invention is not limited in the scope of its application to the particular machine shown and described.

Having thus described my invention, I 50 claim as new and desire to secure by Letters Patent of the United States:

1. A machine for forming a row of punch holes in a piece of stock, having, in combination, a support for the stock, a punch, means 55 for reciprocating the punch, means for feeding the stock intermittently past the punch, and means under control of the operator for varying the direction of the intermittent feed movements during the operation of the 60 machine, said feeding means being constructed and arranged to start each feed movement always at the same point close to the axis of the punch, whereby the spacing of the punch holes in curved rows is substantially uniform.

2. A machine for forming a row of punch holes in a piece of stock, having, in combination, a support for a piece of stock, a punch, means for reciprocating the punch, means for feeding the stock intermittently past the punch, means for varying the direction of the intermittent feed movements, and means for varying the extent of said movements. 70

3. A machine for forming a row of punch holes in a piece of stock, having, in combination, a support for a piece of stock, a punch, means for reciprocating the punch, means for feeding the stock past the punch, said feeding means being constructed and arranged to start each feed movement at a pre-determined point close to the axis of the punch, and means under control of the operator for varying both the direction and the extent of the feed movements while maintaining the location of said starting point 80 unchanged. 85

4. A machine for forming a row of punch holes in a piece of stock, having, in combination, a support for a piece of stock, a punch, means for reciprocating the punch, means for feeding the stock intermittently past the punch, said feeding means comprising gripping members constructed and arranged to permit angular movement of the stock about the point engaged by said members, and means for producing angular movement of the stock. 90 95

5. A machine for forming a row of punch holes in a piece of stock, having, in combination, a support for a piece of stock, a punch, means for reciprocating the punch, means for feeding the stock intermittently past the punch, said feeding means comprising gripping members movable about an axis which extends at right angles to the plane of the support, and means for producing angular movement of the stock. 100 105

6. A machine of the class described having, in combination, a support for a piece of stock, a tool for operating upon said stock, and feed mechanism comprising a reciprocating slide bar, a feed member connected with said bar but capable of movement at an angle to the direction of reciprocation of said bar, a stationary guide for controlling the direction of movement of said feed member, and means for adjusting the position of said guide. 110 115

7. A machine of the class described having, in combination, a support for a piece of stock, a tool for operating upon said stock, and feed mechanism comprising a reciprocating slide bar, a feed member, a link connecting said bar and feed member whereby movement of said bar causes movement 120 of said member, and a guide link connected with said member but not with said bar, said guide link being adjustable to vary the direction of movement of said feed member. 125

8. A machine of the class described hav- 130

- ing, in combination, a support for a piece of stock, a tool for operating upon said stock, and mechanism for feeding said stock past said tool, said feed mechanism comprising an upper and a lower slide bar each having an opening therein, an upper and a lower feed member, the stems of said members passing respectively through said openings, links connecting said members to said bars, a guide member for one of said feed members, and means for holding said guide member in different angular positions with respect to said slide bars to cause said feed members to be swung by said links when said slide bars are reciprocated.
9. A machine of the class described having, in combination, a support for a piece of stock, a tool for operating upon said stock, means for feeding the stock past the tool, and means for feeding a backing strip beneath said stock, said last named means comprising a reel stand, two reels mounted thereon, and means connected with said stock feeding means for frictionally driving one of said reels.
10. A machine of the class described having, in combination, a support for a piece of stock, a tool for operating upon said stock, means for feeding the stock past the tool and means for feeding a backing strip beneath said stock, said last named means comprising a reel stand, a reel carrier pivotally mounted thereon, two reels on said reel carrier, a gear connected with each reel, a frictionally driven gear carried by said stand, 35 and means for holding the gear of either reel in mesh with said driven gear.
11. A machine of the class described, having in combination, a support for a piece of stock, a tool past which the stock is fed and means for feeding a backing strip beneath said stock, said last-named means comprising a reel stand, a frame pivoted to said stand, two reels mounted on said frame, and a driving member into operative relation to 40 which either reel may be swung.
12. A machine of the class described, having in combination, a support for a piece of stock, a tool past which the stock is fed and means for feeding a backing strip beneath said stock, said last-named means comprising a reel stand, a frame pivoted to said stand, two reels rotatably mounted in said frame at points equidistant from said pivot, gears connected with said reels, a driving 50 gear located in position to be capable of meshing with either of the reel gears, and means for holding the frame in position to maintain such meshing.

In testimony whereof I have signed my name to this specification.

ALFRED B. FOWLER.
